ATTORNEY.

UNITED STATES PATENT OFFICE

2,492,370

AUTOMATIC LOAD-RELEASE DEVICE

John C. Rumsey, Mission, Kans.

Application October 6, 1945, Serial No. 620,802

5 Claims. (Cl. 294—83.1)

1

This invention relates to automatic load-release devices and aims to provide a novel and improved construction adapted to satisfy all the requirements of an efficient and practical appliance of this type as regards its load-supporting function, and also provide releasing means adapted to operate to effect release of the load upon slackening of the pull of such load to a predetermined point or fraction of the full actual weight of the load.

The invention relates particularly to devices of this class which are used in aerial transportation and requiring load-releasing means operative to maintain a continuous and positively acting holding and supporting connection with the load, and including means also operating to insure instant release of said supporting connection at the landing point or place of delivery of the load.

For the embodiment of my invention, I provide a device comprising separable connecting elements designed for attachment to the transport or carrier (such as a parachute) and to the load respectively, and also latching means operative to maintain said elements connected in positively latched relation under the weight of the load until automatically released by any slackening of the pull thereon to a given predetermined point or weight factor equivalent to but a small fraction of the actual full weight of the load.

For accomplishing these objects of the invention I provide a construction comprising separable elements and automatic releasing means of the character referred to and including a yielding type of load-supporting means having a given predetermined load-carrying capacity, and combined with supporting means operating automatically to receive and carry any load in excess of said given capacity, but to which no part of the load is transmitted or applied except when the capacity of said yielding supporting means is exceeded.

With the foregoing general objects in view the invention will now be described by reference to the accompanying drawing illustrating one form of construction which I have devised and found to be a suitable and practical embodiment of the proposed improvements, after which those features and combinations deemed to be novel and patentable will be particularly set forth and claimed.

In the drawing:

Figure 1 is a sectional elevation illustrating a load-releasing appliance constructed in accordance with the present invention and showing the

2

parts in initially latched relation, with dotted lines indicating the releasing position of the detent means or latching mechanism;

Figure 2 is a longitudinal sectional view of the appliance, representing a section taken on the line 2—2 of Figure 1;

Figure 3 is a similar sectional view, showing only the lower parts appearing in Figure 2, and illustrating the yielding supporting means extended and parts of the structure shifted for imposing a part of the load upon the positive load-supporting elements of the appliance; and

Figures 4 and 5 are transverse sectional views, representing sections taken on the lines 4—4 and 5—5, respectively, of Figure 1.

Referring now to the accompanying drawing in detail, my improved load-releasing appliance is illustrated as comprising a link connection 10 designed to be attached to the supporting means

20 of the carrier, such as the harness suspended from a parachute or the like (not shown). This link 10 is swiveled to a strap 12 secured by rivets 13 to the opposite sides of a casing 14 which is provided with pins 15 on which are pivotally mounted the upper ends of a pair of automatic releasing arms 16. These arms 16 are of tubular or channel construction, with opposed longitudinal slots 18 designed for slidably accommodating the opposite edges of a plate 20 carrying 30 the latching means hereinafter referred to. The arms 16 moreover are provided with a set of supporting and latching pins 22 for supporting and releasing engagement with a set of recesses or notches 24 in the opposite side edges of the plate 35 20, and also with the opposite ends of a release bar 26 to which is anchored the upper end of a coil spring 28 as represented in Figures 1 and 2. The pins 15 also serve to support a plate 30 fitting in the upper ends of the slots 18 and limiting the inward swinging movement of the arms 40 16, which are swung normally outward into releasing position (as represented by dotted lines in Figure 1) by the action of a spring 32 held in place by lugs 33 on the upper margins of said plate 30 and with the free ends of said spring 45 projecting into operative engagement with the interior of the upper ends of the arms 16 to the outside of their pivot points 15.

The latching and releasing means, which is 50 carried by the plate 20, comprises detent elements made up of a pair of detent plates or levers 34 mounted on the opposite faces of the plate 20 and between the upper notches or recesses 24 and fulcrumed on a pivot pin 36 located somewhat nearer to one side of the plate than the

other, for reasons which will hereafter appear. The ends of the levers 34 are formed with notches 40 opening in opposite directions, thus providing terminal detent fingers 42 for the corresponding pins 22 of the arms 16 when the levers are in the position illustrated in Figure 1. To the longer arm of the levers 34 is pivotally connected a pair of strap links or bars 44 on the opposite faces of the plate 20 and connected by pins 46 operating through suitable slots 47 and 48 in said plate, the upper pin 46 providing a pivotal connection with the detent levers 34, and the upper slot 47 being slightly curved to accommodate the corresponding movement of said upper pin 46 about the axis or pivot pin 36.

To the lower end of the bars 44 is attached a swivel link 50, which in turn is pivotally embraced (at 52) by the intermediate portion of a strap link bar 54 with which it is adapted to cooperate in forming a toggle link connection between the lower end of the bars 44 and a loop 56 swiveled to one end of the bar 54. The other end of said bar 54 is attached at 55 to the lower end of the coil spring 28, as shown in Figures 1, 2 and 3. The loop 56 is designed to form the connecting link, for attachment to the load (not shown).

In the use and operation of the appliance, the parts thereof are assembled in the relation illustrated by the full lines in Figures 1 and 2, with the bar 26 supported on the upper pins 22 and the plate 20 also supported by engagement of its side notches 24 with the other pins 22 of the arms 16. First a pull is applied to the bars 44 for swinging the detent levers 34 into position for bringing the detent fingers into place as shown in Figure 1 for latching the arms 16, and a frangible pin 60 is inserted into registering openings 62 in said levers and plate 20, for the purpose of preventing any casual release of the arms 16 during the necessary handling of the appliance before the final release operation.

Now the purpose of the spring 28 is to provide a means for supporting a fraction of the load (on the upper pins 22 of the arms 16) during the initial operation and up to the application of the main portion of the load into supported relation to the other pins 22 through the medium of the plate 20, which takes place as the spring 28 is expanded under the pull of the load on the link 54 and straightening of the toggle connection 50-54, with the result that the pin 60 is broken, thus allowing the detent levers 34 to swing freely in either direction, that is, for either maintaining the latching function by means of the detent fingers 42 under the continued pull of the load; or, for releasing the arms 16 as the detent levers 34 are swung in the opposite direction (into the position indicated by the dotted lines in Figure 1) by the pull of the spring 28 following the release of the main portion of the load.

It will thus be seen that the spring 28 assumes three different working positions corresponding to three different working positions of the detent levers 34: first, the initial latching position of said levers as represented by the full lines in Figure 1, in which position said spring is under a slight initial tension; second, the position following clockwise movement of said detent levers 34 under the pull of the load, for shearing the pin 60, in which movement the spring 28 reaches its fully extended position as indicated in Figure 3, when the greater portion of the load is applied to and supported by the plate 20; and finally, the releasing position, on reverse movement of said detent levers 34 in response to the action of the spring 28 following release of the load on

the plate 20, thereby effecting the unlatching or release of the arms 16 and allowing the latter to be spread outward into releasing position by action of the spring 32 as represented by the dotted lines in Figure 1.

It will be understood that the type of spring 28 to be used will be governed by the proportion of the maximum load which is to be supported thereby up to the point of application of the main portion of the load to the plate 20 following the straightening of the toggle connection thereto and the full expansion of said spring as illustrated in Figure 3. The percentage of the load which is supported by the spring 28 under such conditions is therefore a predetermined quantity or factor, as represented by that proportion of the load which is to remain supported by said spring after, say, initial contact by the load with the ground, following which the action of said spring will continue to prevent any final operation of the load-releasing mechanism until substantially the full spring action of the spring is taken up; that is to say, any varying pull of the load following ground contact, or any fluctuations in the pulling action of the parachute or carrier supporting connection, will be automatically absorbed by the action of the spring 28, as it contracts, and without any final release of the load-releasing arms 16 until a predetermined point is reached, at or about the point of complete contraction of the spring, which is governed by the strength or tensional capacity of the particular spring being used.

This final release of the arms 16 of course allows the bar 26 to become dislodged from the upper supporting pins 22 (as represented by dotted lines in Figure 1), and hence effects complete release of the latching and detent means from said arms, and therefore entire separation of the parts of the device attached to the load and the parachute or carrier, respectively.

While I have illustrated and described what I have found to represent a suitable embodiment of my improved load-releasing appliance, I wish to be understood as reserving the right to make such changes or modifications as may fall within the scope of my invention as defined by the following claims.

What I claim is:

1. Load-releasing means for releasing loads from carriers, comprising separable connector members for attachment to the carrier and to the load respectively, one of said members being provided with latching means mounted for relative movement thereon and actuated automatically under the pull of the load into latching engagement with the other of said members and the latter having automatically separating arms for releasable engagement by said latching means, and yielding means acting in opposition to the weight of the load to effect unlatching of said latching means and arranged to complete said unlatching operation by substantially full collapse of said yielding means.

2. Load-releasing means for releasing loads from parachute carriers and the like, comprising separable connector members for attachment to the carrier and to the load respectively, one of said members being provided with latching means actuated under the pull of the load into latching engagement with the other of said members and the latter having automatically separating arms for releasable engagement by said latching means, and yielding means releasably supported by said arms and tending normally to effect unlatching

of said latching means and arranged to complete said unlatching operation by the substantially full collapse of said yielding means.

3. Load-releasing means for releasing loads from parachute carriers and the like, comprising separable connector members for attachment to the carrier and to the load respectively, one of said members being provided with latching means pivotally mounted thereon and actuated automatically under the pull of the load into latching engagement with the other of said members and the latter having automatically separating arms for releasable engagement by said latching means, yielding means tending to effect unlatching of said latching means in opposition to the weight of the load and operative on substantially full collapse of said yielding means to complete said unlatching operation, and frangible means for temporarily locking said latching means and rendered inoperative by movement of said latching means under the pull of the load.

4. Load-releasing means for releasing loads from parachute carriers and the like, comprising separable connector members for attachment to the carrier and to the load respectively, one of said members being provided with latching means operable under the pull of the load into latching engagement with the other of said members and the latter having automatically separating arms for releasable engagement by said latching means, yielding means releasably supported by said arms and tending normally to effect unlatching of said latching means, and load-supporting means at-

tached to said yielding means and provided with an operative toggle connection to said latching means.

5. Load-releasing means for releasing loads from carriers, comprising separable connector members for attachment to the carrier and to the load respectively, one of said members being provided with latching means operable automatically under the pull of the load into latching engagement with the other of said members and the latter having automatically spreading arms for releasable engagement by said latching means, yielding means releasably supported by said arms and tending normally to effect unlatching of said latching means, frangible means for temporarily locking said latching means and rendered inoperative by movement of said latching means under the pull of the load, and load-supporting means attached to said yielding means and provided with a toggle link connection with said latching means.
